BIT CONTROL FOR PERCUSSIVE TOOLS

Alonzo G. Decker, Jr., Baltimore, Md., assignor
to The Black and Decker Manufacturing Com-
pany, a corporation of Maryland

Application November 1, 1940, Serial No. 363,811

3 Claims. (Cl. 255—37)

In the operation of power hammers, particularly those of the high power and high frequency of impact which is now established practice, the resulting vibration is excessive and operating handles usually in the form of a transverse arm whereby the operation of the drill or other bit is directed, are found to be of relatively short life due to crystallization resulting from the vibration to which they are subjected. Also the direction of the bit by means of the operating handles now in use involves the transmission to the hand of the operator of the excessive vibration due to the high power and high frequency impact. A further undesirable incident due to the use of the prior apparatus is the transmission through the operating handle to the hands of the operator of the heat which is generated in the tool.

The result of the vibration and heat thus transmitted to and through the handle to the hand of the operator is of primary importance in its effect on the operator made apparent by weariness and loss of accuracy and efficiency in directing the tool, thus affecting adversely the quality and efficiency of all operations performed under these conditions.

The object of the present invention is to provide an operating handle for directing the drill or other bit particularly a connection of the handle to the bit which eliminates or at least greatly reduces the vibration which is transmitted to the handle and hence to the hand of the operator, thus increasing the life of the operating handle and avoiding harmful weariness and inconvenience to the operator and particularly loss of accuracy and efficiency, as above.

The operating handle construction and connection of the invention also limits and reduces the transmission of heat from the bit to the handle and hence to the hand of the operator.

The improved result attained is largely dependent on the provision in the connection between the operating handle and the bit shank or bit holder shank which, for the purposes in hand, are considered identical, of a lost motion which in operation gives relative play to the bit and handle with consequent reduction of the vibratory effect transmitted to the handle. The contact between the bit shank and handle is also reduced and rendered intermittent in operation by said lost motion. The invention also contemplates the use of a resilient cushion between the connecting members which both limits the relative motion and takes up the vibration, and having heat insulating properties reduces the

passage of heat below that which occurs in the old type of connection.

In the accompanying drawing, I have illustrated an operating handle embodying the features of the invention, the same being adapted for use with drills and similar bits for operation by percussive tools as electric and other power hammers, particularly those of the portable type.

In the drawing:

Fig. 1 is a side elevation of a bit holder and drill bit therein, the same being of the type used with electric and other portable power hammers the illustration including an operating handle attached directly to the bit holder shank and indirectly to the bit.

Fig. 2 is a similar view on a reduced scale of an electric hammer equipped in accordance with Fig. 1.

Fig. 3 is a horizontal section on the lines 3—3 in Fig. 1 showing the tool holder shank and handle and the handle ring in cross section.

Referring to the drawing by numerals each of which is used to indicate the same or similar parts in the different figures, the construction shown comprises a tool holder 1, having a drill bit 2 and an operating handle 3 in their normal operating relation.

The tool holder 1 in the form shown comprises a socket member 4 and a shank 5 extending upwardly from the socket. The tail 6 of the bit is seated in the tapered bore 7 in the socket 4 and the socket is provided with a transverse aperture 8 through which a suitable implement may be inserted to loosen the bit. When the bit is thus attached to the holder the bit and holder are rigidly connected.

The upper end of the holder shank 5 is reduced at 9 to fit in the nose of the hammer in accordance with the usual practice. In the form shown, the tool holder shank is shouldered peripherally at 10 at the bottom of said reduced portion 9, the details above described being regular practice.

Important difficulties incident to the operation of the prior art tools of this general type are found to be due to the transmission to the handle and hence to the hands of the operator of the vibrations and the heat due to the impact of the hammer, with the harmful results in the way of the deterioration of the handle by crystallization and loss of efficient control due to weariness and undue heating or burning of the hands, as already pointed out.

The present invention is found to reduce and practically eliminate these difficulties.

An important feature of this invention on which the result attained is largely dependent resides in the provision of a connection of the operating handle to the bit either directly or through the tool holder, such connection giving a control of the bit or drill which is sufficiently positive for accurate placement and direction of the holes or work and at the same time providing clearance, reduction of contact and lost motion between the handle and bit sufficient to reduce or prevent transmission of vibration due to the hammer impact, and to similarly reduce or prevent the passage of heat by conduction from the bit to the handle and hence to the hand of the operator.

To this end the tool holder or shank which is rigidly attached to the bit is provided at any suitable point, most conveniently above the socket 4 with a series of splines 12 and intermediate grooves 14 between the splines, which, in the form shown, are substantially parallel to the axis of the holder and bit.

For co-operation with the tool holder and particularly the splines 12 and grooves 14 the drawing shows the handle 3 provided at its inner end with a ring portion 15 which encloses or encircles the tool holder shank immediately above the socket member 4, said ring 15 having its central aperture 16 formed with alternate inwardly disposed splines 17 and grooves 18 which receive and enter respectively the splines 12 and grooves 14 on and in the shank 5. It is important that there is considerable clearance at 19, 19', 19'' between ring 15 and holder 1 and particularly between the interengaging splines of the ring and holder and as a consequence there is a considerable lost motion between the handle and the holder and the bit therein so that the handle is not in any sense rigid with the tool holder 1 or with the bit 2. The engagement is, however, sufficiently positive to give accurate direction of the bit by the handle and accurate placement and direction of the holes or other work, with reduction and breakage of contact between the bit and holder in operation.

The splines 12 on the tool holder are in the preferred form of the invention shown of not much greater axial length than the width of ring 15 and there is a washer or other suitable ring 20 which fits down over the shank 5 of the tool holder and rests on the top of the splines 12 or on any suitable stop, being secured in a manner to be described or in any suitable manner, and serving as a stop for the handle.

In the form shown in Fig. 1, the tool holder is provided beneath the handle ring 15 with a shoulder 21 formed at the upper end of the socket or otherwise positively related to the shank and the space between the bottom of the washer 20 and the top of the shoulder 21 is greater than the width of the handle ring 15 providing for vertical as well as lateral and rotary play of the handle 3 relative to the bit 2 and/or bit holder 1 and vice versa.

A convenient manner of securing the stop ring 20 is as follows:

In the form shown in Fig. 1 the tool holder shank 5 is provided with a peripheral abutment 22 at a convenient point spaced above the splines 12 and the tool holder 5 is to best advantage peripherally grooved at 24 immediately below the abutment 22. In passing the ring 20 downwardly over the shank 5, it is followed by a sleeve 25 which is of sufficient length to extend from the abutment 22 to the stop ring 20. The upper

edge of the sleeve 25 at 26 is then rolled inwardly into the groove 24 and against the shoulder 22, completing the assembly of the handle and tool holder, the specific details being subject to variation.

While the connection of the handle to the bit holder or bit is sufficiently positive to give the desired control of the latter for accurate work, bit 2 is thus permitted to have a limited movement up and down or axially and relatively to the handle and there is also a sufficient degree of lost motion or lateral and/or rotative yielding of the bit relatively to the handle so that contact between the bit or holder and the handle is greatly reduced there being no continuous and positive contact between the handle ring 15 of handle 3 and the bit 2 and/or tool holder 1 and the vibrations are mainly independent of the handle. Consequently, the tendency to the transmission of vibration and heat from the bit through the handle to the hand of the operator resulting in discomfort, weariness and loss of efficiency on the part of the operator is greatly reduced or almost entirely prevented and with reduction of vibration of the handle the tendency to failure of the handle by crystallization is greatly reduced.

Fig. 2 shows the handle 3 and tool or bit holder 1 and bit 2 assembled in operative relation with an electric hammer 27.

The operation will be clear from the preamble and the description of the figures.

What I claim as new and desire to secure by Letters Patent is:

1. The combination with a bit holder for operation in impact transmitting relation to and with a power hammer bit, of an operating handle elongated transversely to the length of the bit, said handle having an apertured portion enclosing said bit holder and a bit controlling connection between the said enclosing portion and the bit holder, said connection comprising co-operating splines and grooves inwardly disposed on the said enclosing portion and outwardly disposed splines and grooves on said bit holder, said splines and grooves on the enclosing portion and on the bit holder being arranged in inter-engaging relation and having an excess of clearance radially and circumferentially, said holder having an upwardly disposed shoulder below the enclosing portion to support the handle on the holder, said holder also having a sleeve encircling the same and removably secured thereto above said enclosing portion and a ring encircling said holder above said enclosing portion, and engaged on one side by the lower end of said sleeve and on the other side by said enclosing portion, whereby the holder is supported on the handle.

2. The combination with a bit socket member for operation in impact transmitting relation to and with a power hammer bit, of an operating handle elongated transversely to the axis of the bit and socket member, said handle having an apertured portion enclosing said bit socket member and a bit controlling connection between said enclosing portion and the bit socket member, said connection comprising co-operating splines and grooves on the said enclosing portion and said bit socket member respectively, said splines and grooves on the socket member and enclosing portion respectively having an excess clearance radially and circumferentially, and abutment means on said socket member above and below said enclosing portion, thereby the handle may be at times supported on the socket member and

at other times the socket member may be supported on the handle one of the abutment means being removable and both said abutment means being supported on the socket, the cooperating surfaces between the abutment means being parallel to the axis of the socket member, and the abutment means being separate from the handle structure.

3. The combination with a bit holder for operation in impact transmitting relation to and with a power hammer bit, of an operating handle elongated transversely to the axis of the bit and holder, said handle having an apertured portion enclosing said bit holder and a bit controlling connection between said enclosing portion and the bit holder, said connection comprising co-

operating splines and grooves on the said enclosing portion and said bit holder respectively, said splines and grooves having an excess clearance radially and circumferentially, and abutment 5 means on said holder above and below said enclosing portion, thereby the handle may be at times supported on the holder and at other times the holder may be supported on the handle, one said abutment being in the form of a shoulder, 10 a sleeve encircling the holder and supporting said shoulder, said sleeve being removably engaged with and secured to said holder to provide for convenient attachment and removable of the handle.
